United States Patent Office.

A. W. SCHARIT, OF ST. LOUIS, MISSOURI, L. A. HUDSON, OF SYRACUSE, NEW YORK.
AND DARIUS LYMAN, OF PARKMAN, OHIO

Letters Patent No. 96,488, dated November 2, 1869.

ELECTRO-MAGNETIC GAS-LIGHTING APPARATUS.

The Schedule referred to in these Letters Patent and making part or the same.

To all whom it may concern:

Be it known that your petitioners, A. W. SCHARIT, of St. Louis, Missouri, L. A. HUDSON, of Syracuse, New York, and DARIUS LYMAN, of Parkman, Ohio, all citizens of the United States, temporarily residing in Washington, have invented a new and improved mode of lighting and extinguishing simultaneously, or nearly so, numerous jets of gas for illuminating streets, and public or private places, or edifices, by means hitherto unknown, which we call the "American Pharcion," being a combination of chemical, electrical, and mechanical devices to that end, in which—

First. We use chemical substances or products for producing light, when required to ignite the gas.

Second. We use electricity or the electro-magnet to release machinery propelled by mechanical forces.

Third. We use machinery to bring chemical substances or products of a pyrophorous character in close proximity to the gas-burner, while we cause the isochronical movements of the mechanism so to operate as to turn on and off the several jets of gas, and to ignite the same, by its manipulation of the aforesaid chemicals or chemical products, when released by the electro-magnet for such purpose.

This combination of chemical, electrical, and mechanical forces is so devised and constructed as to effect the simultaneous or nearly simultaneous lighting and extinguishing of any given number of gas-jets to which the same may be adjusted and connected with a battery.

To enable others skilled in the art to make and use our invention, we will proceed to describe its construction and operation.

To this end, we have essayed our invention in various ways, some of which are as follows:

Attaching our devices to the ordinary gas-pipes, supplied with carburetted hydrogen or common illuminating-gas, we use the usual plug-cock, to which, in some instances, we make our connections, as will appear in the several modifications hereinafter shown and described. Yet we do not confine ourselves to this form of cock or valve, but would prefer some more facile-working form, such, for instance, as our "elastic chamber-valve," as shown in the annexed drawing, and made part of these specifications, as delineated on Sheet No. 1, thus, wherein—

A represents the gas-pipe and burner.

B, in Figure 1, is the frame, attached to the gas-pipe, and sustaining the spring and gas-lifter or elevator.

It will be seen, by the form of the elevator D, that as the valve-lever G falls into the depressions, or rises, the valve will be opened or closed, the stem of the valve being attached to the valve-lever.

In Figures 4, 5, 6, and 7—

A represents the valve-stock or pipe, shown in different positions.

Fig. 4 shows the general appearance, an edge view of the rubber packing B, also the end of the lever E and lever-guide D'.

Fig. 5 is a top view, showing the flange-binding C as fastened to the stock or pipe by screws, with the circular opening, showing also the rubber or elastic packing B', and the crossing of the valve-lever E and its guides D' D''.

Fig. 6 is an end view, showing the valve-lever and its connection with the stem of the valve, &c.

Fig. 7 is a top view, with the other parts removed.

The dotted lines H represent the passage, ascending or descending, uniting with or opening into the valve-chamber at the orifice and valve-seat G.

The lines I represent the outlet as connected with the orifice I.

Figure 8 is the valve K, with its guide L, the office of which is to insure its return to its seat.

M is a button or flange on the valve-stem, directly under the rubber packing, as represented at B'.

The above-described valve is further represented on said sheet, in the first modification of our devices, as follows, (see drawings:)

This modification embraces chemical pyrophori, as Honberg's pyrophorus, the phosphoric-match vial, the hydrogen gas, and platinum sponge, or other gas, so manipulated by the mechanism as to ignite the gas furnished for illumination; thus:

Figures 1 and 2 represent the temporary magnet, T T, its armature a a, guide-rod S, and armature-guides U U.

W is a cam, the office of which is to elevate the bar bearing the platinum sponge-cup, or pyrophorous vial C', whichever of these devices may be used to ignite the gas, and also the match-rod D', the upper portion of which, being brought forward, enters the pyrophoretic magazine, and on its return rests a time in the current of gas, thus communicating light.

Fig. 2 represents the double frame-work B B B, and the train of gearing H, P, and R, connected by pinions. The chief object of this train is to reduce the power of the main-spring or motive-force in all the forms, so as to bring the resistance within the capacity of a small electro-magnetic force to release and control its action.

Figure 3 is an edge view, showing the pipes and valve-stock connected with them, also showing the relative position of the parts.

B is the frame-work.

C, the case or drum, enclosing the main-spring or

shaft, with which the valve-elevator, or cam-wheel D, and main wheel of the clock-work, train H working into the pinion I.

K is the second wheel on the shaft, with pinion I working into pinion N on shaft, with escapement-wheel P.

Q is a shaft, to which is attached the wire L, which, rising on the pins in wheel K, relieves the catch-wire, attached to same shaft from the pin or stop in the escape-wheel P, thus allowing the force of the spring in C to rotate the cam-wheel D and main wheel of the train H, thus opening or closing the valve, and starting the train of wheels, and also the cam W, which lifts the bar B', to the upper end of which is the platinum sponge-cup C, or pyrophoretic vial, or other chemical substance to light the jet of gas. A pin, V, in the cam W, at the same time acts on the lever D', which carries the match E.

T is the temporary magnet, the action of which is, by its force through the armature-rod, to release the catch O from the shaft Q, thus allowing the machinery to start.

The magnetic force being removed, the pins in wheel K lift the lever L, attached to shaft Q, and depress the escape-wire, attached to same shaft, which, when the escape-wheel comes around, takes hold of the pin in it, at the same time the catch O takes hold of the hook in shaft Q, and further action of the machinery is arrested.

In fig. 2, I' is the hydrogen-gas pipe and jet for carrying that gas to the platinum sponge in cup C. To this jet is a rubber hose, or other pipe leading from the gas-holder or generator. This pure hydrogen-holder or generator may be located and the gas generated in the body or base of the post or near the main pipe, or wherever found most convenient.

The wires connecting the magnets and battery may be run above ground, on or above the line of the range of street lights, or under ground, as may be deemed expedient, and may be so arranged as to be made available for a fire-alarm, municipal or local telegraphic purposes.

Sheet of drawings No. 2, hereto annexed, and made a part of these specifications, represent another modification of our devices for opening and closing gas-cocks, and igniting the gas by means of pyrotechnic bands passing over pulleys, and intermittently or at proportionate and proper distances charged with pyrophorous and combustible material, or continuous chain-work of lucifer-match fuses, carried to the gas-jet by an incombustible band passing around pulleys, and the match or fuse being ignited by percussion or friction, said band being made of asbestos, incombustible cloth, or other flexible material which may be deemed suitable and proper, and properly provided with ribbons or coils of the most approved preparation of match-paper for the end designed.

On this sheet, fig. 1 is a side view, showing A, the gas-pipe, attached to the frame-work B by the supports O.

P P are adjusting-screws.

H is a drum, carrying the band I over the pulley K. Q is the pulley-support, and

S, the gas-burner.

I is a part of the escapement-wheel.

aa are spools for the lighting-band.

Fig. No. 2 is a view of the opposite side.

The same letters refer to the same parts.

T is the escape-wheel in full.

V, the pendulum-rod, and

U, the pallets which act on the escape-wheel.

Y is a slot-guide for the pendulum.

XX are the poles of the temporary magnet; and

W, the armature, one end of which is hinged to one of the poles. The other end is notched, so that when relieved by the magnetic force it is borne up

by the spring Z, and catches the pendulum, and thus arrests the action of the machinery.

Figure 3 is an edge-view, showing portions of the works otherwise concealed.

Beginning with the gas-pipe A, the supports O O are more clearly shown.

P are the set-screws.

S, gas-burner.

H, the face of the drum, which is attached to the key of the cock.

The dotted line is the band I, and K shows the face of the small pulley.

B is the frame.

C is the spring-case, and

D, the driving-wheel, forming the head of case.

No. 2 is the ratchet-wheel.

The wheel D works into the pinion E.

On its shaft is wheel F, and the clutch No. 1, which connects with the key of the cock N.

G is a pinion on shaft with ratchet-wheel T, and is driven by wheel F.

M are cams on the side of wheel F, that operate the igniter L.

U is the click or escapement.

V, the pendulum working in guide Y.

X is the temporary magnet.

W, its armature.

aa, an edge view of one of the spools.

In the several devices above shown and described, it is proposed to so construct the mechanical forces as to wind up the spring once in about thirty days, or, using more powerful means of propelling the same, once in sixty days.

Sheet of drawings No. 3, made part of these specifications, shows another modification, in which the gas-pipe A passes through the machine, and forms the centre on which the spring acts, as will be described in fig. 3.

B is the spring-case, to which is attached the driving-wheel C, working into pinion D, which is connected by shaft with second wheel E, which works into pinion F on shaft with third wheel F, which works into pinion G on shaft with escape-wheel 5.

On the top of the shaft on which is pinion D, is the fourth wheel G, acting on pinion H on screw I.

The screw I rotates the pinion K, which is on the key of the gas-cock.

Below the frame is another pinion, L, on shaft M, working into the main wheel.

Above the frame is another pinion, N, working in the wheel O.

The wheel O is on the shaft with drum P, that carries endless chain or band, connecting with band-pulley R.

On the top of shaft M is a cog-wheel, S, driving-pinion T, and shaft, on the top of which is the igniter V.

W is the pulley-support.

Referring to fig. 3—

1 is the temporary magnet;

2, the armature; and

3, a pin descending from the armature through the frame-plate, and is the pendulum-catch or stop.

4 is the pendulum, and

5 5 are the escapement and wheel.

6 and 7 are the ratchet-wheel and clutch or click.

The dotted lines No. 10 represent a tubular shaft, through which the gas-pipe passes.

To the upper end is attached the ratchet-wheel No. 6, and passing through the spring-case is the axis, to which one end of the spring is fixed.

To the lower end is fastened a collar by set-screw, from which extends the winding-levers No. 9.

Figure 4 is a section, showing the position of train of wheels, with the escapement and pendulum.

Any one of the above devices may be used sepa-

rately, or in conjunction with the other, care being taken that the movements of the machinery be made to operate in isochronical precision.

We do not claim to turn on and off, nor to light gas by electricity; but

What we do claim, and desire to secure by Letters Patent, is—

1. A gas-lighting and extinguishing apparatus, combining in its construction a series of gear-wheels, to be driven by a spring or weight, a cup or other vessel containing pyrophorous material, a cam for elevating such cup or vessel, a match-rod for inserting the match into the pyrophorous material, and afterward bringing it in contact with the gas-jet, an elastic chambered valve for controlling the flow of gas to the burner, and a wheel, having a cam-shaped or serrated surface, for controlling the movements of such valve, all ar-

ranged to operate substantially as and for the purpose set forth.

2. In combination with the elements of the preceding clause, the armature of an electro-magnet, for the purpose of releasing such parts from the control of the spring or weight, and thus allowing the gas to be shut off from the burner, substantially in the manner set forth.

3. The described construction of the elastic chambered valve, substantially as and for the purpose set forth.
